UNITED STATES PATENT OFFICE.

WEBSTER JOHN BEVILLE, OF LONDON, ENGLAND.

ILLUMINATED APPARATUS FOR DISPLAYING AND ADVERTISING PURPOSES.

1,419,899.

Specification of Letters Patent. Patented June 13, 1922.

Application filed February 8, 1922. Serial No. 534,980.

To all whom it may concern:

Be it known that I, WEBSTER JOHN BEVILLE, a subject of the King of Great Britain and Ireland, residing at 2 Lorraine Place, Holloway Road, London, N. 7, England, have invented certain new and useful Improvements in Illuminated Apparatus for Displaying and Advertising Purposes (for which I have filed an application in Great Britain Sept. 15, 1920, Patent No. 173,283), of which the following is a specification.

The main object of the invention is to provide an apparatus for displaying goods consisting of a stationary stage-like chamber by means of which one or more objects placed in the chamber will be illuminated by both direct and reflected rays of light emanating from a lamp contained in a compartment hidden from external observation. A further object of the invention is to so construct such an apparatus that it may be utilized for displaying advertisements.

The invention will be mainly described as it may be constructed if the compartment containing the lamp is located in the upper part of the structure and only a single object is displayed.

According to the invention a stationary stage-like chamber of the necessary size is used, said chamber being open at its front side. Said front side is provided with a border or frame of suitable nature, for instance a frame resembling an ordinary picture frame, while the interior of the lower part of the chamber is provided with a shelf or the like for supporting the object to be displayed. Said chamber may be of box-form and the solid walls of same be connected to one another in such manner that they can be readily taken apart and put together. Alternatively, the side walls of the chamber may be solid and the rear wall of the chamber consist of curtains supported from a horizontally disposed rod of curved form connected to said side walls. Within a compartment located in the upper part of the chamber is supported an incandescent electric lamp which projects into a drum-like reflecting structure that is arranged at an angle to the vertical centre line of the chamber. Enclosing said angularly disposed reflecting structure is a rotary drum adapted to produce alternate lighting effects, such as changes of colour, flickering, intermittent illumination or other effects. This rotary drum which is caused to rotate, in known

manner, by the air heated by said lamp is provided with a supplementary reflector adapted to receive rays of light from said drum-like structure and reflect them or such of the rays of light as would not otherwise reach the object on to the object contained in the chamber of the apparatus. The rotary drum may be used by itself, but is preferably surrounded by a stationary drum. When the chamber is to be illuminated otherwise than at its centre or when advertisements at the sides of the chamber are to be illuminated the side walls of said angularly disposed reflecting structure are formed with openings, and supplementary reflectors are arranged at the sides of the rotary drum, or at the sides of the stationary drum, when the rotary drum is surrounded by a stationary drum, by means of which supplementary reflectors rays of light passing through the openings formed in the side walls of the angularly disposed reflecting structure will be reflected so as to illuminate the lateral parts of the interior of the chamber or the advertisements at the sides of the chamber. The compartment containing the illuminating and reflecting parts of the apparatus are enclosed so as to be hidden from external observation.

The accompanying drawings illustrate an embodiment of the improved apparatus in which both rotary and stationary drums are employed and the sides of the chamber of the apparatus are assumed to be provided with advertisements.

Fig. 1 is an elevation illustrating said embodiment, from which has been omitted the curtain which hides from view the parts by which is effected the illumination of the object to be displayed. Fig. 2 is a vertical section of the apparatus. Fig. 3 is a sectional plan of the apparatus, the section being taken through the upper part of the chamber of the apparatus. Fig. 4 is a second sectional plan of the apparatus, the section being taken through the lower part of said chamber.

1 is the base of the chamber of the apparatus and 2 are the side walls of the chamber. 3 is the rear wall of the chamber consisting of a curtain or curtains supported from a horizontally disposed rod 4 of curved shape. 5 are braces secured at their ends to the side walls 2 for the purpose of imparting rigidity to the structure. 6 is a shelf which serves as a support for the object to be dis-

played and is preferably adjustable in a vertical direction to suit objects of different sizes. 7 is a second shelf or partition located at a suitable distance from the top of the chamber. 8 is a curtain which hides from external observation the part of the chamber above the partition 7. 9 is a drum-like structure which is supported in position above the partition 7, preferably in such manner that it can be readily removed, with its axis at a suitable angle to the centre line of the chamber. 10 is an incandescent electric lamp which is supported from the partition 7 and projects into the drum-like structure 9. This structure 9, which is open at its lower end and is closed at its upper end, is constructed of tin-plate and its upper end is fitted with strips of silvered glass 11, so that the rays of light emitted from the lamp 10 will be reflected and pass out of the lower or open end of the structure. 12 is a rotary drum surrounding the drum-like structure 9. This drum 12 is constructed of mica, so as to be as light as possible, and is coated with black paint on its periphery with the exception of one or more spaces which are left uncovered so as to provide one or more transparent panels. The drum 12 is rotatably supported from the drum-like structure 9 by means of a centre or needle 13, and is provided at its top with vanes 14 against which the air heated by the lamp 10 will impinge and cause the drum to be rotated. 15 is a stationary drum surrounding the rotary drum 12 and secured to the partition 7. The drum 15 is provided at its back with an opening 16 to allow of the passage of light from the drum-like structure 9, and a reflector 17, of or approximately of the shape shown, is secured in position around said opening. The walls of this reflector which face the opening 16 are preferably fitted with silvered glass 18 on which part of the rays of light reflected from the strips of silvered glass 11 in the upper end of the drum-like structure 9 will fall and be reflected on to the object supported on the shelf 6. If it is desired that the lateral parts of the interior of the chamber of the apparatus shall be illuminated or if the sides of the chamber are to be provided with advertisements which are to be illuminated openings 19 are formed in the sides of the drum-like structure 9 and openings 20 in the stationary drum 15 in a position facing the openings 19, and reflectors 21, of or approximately of the shape shown, are secured to the partition 7 opposite the openings 20 and above openings 22, see Fig. 3, formed in said partition. 60 When the sides of the chamber are provided with advertisements the latter are arranged at a suitable angle to the side walls of the chamber of the apparatus, and the rays of light reflected from the reflectors 21 are conducted by means of passages or conduits 23

into the spaces 24 obtaining at the backs of said advertisements. The walls 25 of said spaces other than the front walls thereof are lined with or consist of tin-plate or other reflecting material, so that the rays of light 70 passing into the spaces 24 will be reflected on to said front wall. Said front walls, though they may consist of pieces of glass bearing translucent letters on an opaque ground, preferably consist of pieces of prismatic glass 26 on the front faces of which are secured the advertisements consisting of stencils or the like. 75

With an apparatus constructed as above described varying effects may be obtained. 80 For instance the periphery of the rotary drum may be provided, by covering same with black paint, as above described, with suitably spaced translucent panels, so that as the drum revolves the object to be displayed 85 and the advertisements at the sides of the chamber, will be successively illuminated and deprived of light. Or the periphery of the rotary drum may be painted with a succession of colours, so that as the drum revolves 90 the object, and the advertisements at the sides of the chamber will be successively illuminated in different colours. Or a flickering effect may be obtained by providing the rotary drum with vertically disposed 95 opaque and transparent strips and the inner ends of the supplementary reflectors with grids.

The construction of apparatus described above may be varied. 100

For instance the chamber of the apparatus may be open at two of its sides, in which case the objects to be displayed in the two parts of the chamber could be illuminated by means of two annularly disposed drum-like structures enclosed within a single rotary drum, and as already mentioned a rotary drum only can be employed, the outer or stationary drum being dispensed with. 105

What I have invented and desire to secure by Letters Patent of the United States is as follows:—

1. An illuminated apparatus for displaying an object comprising a stage-like chamber open at its front, a compartment in said chamber hidden from external observation and separated from the rest of the chamber by a partition, a reflector supported in position in said compartment with its axis at an angle to the normal, a lamp projecting into said reflector, an opening at the rear of said partition for the passage of light into said chamber, and a rotary drum surrounding said reflector, substantially as described. 115 120

2. An illuminated apparatus for displaying an object comprising a stage-like chamber open at its front, a compartment in said chamber hidden from external observation and separated from the rest of the chamber by a partition, a reflector supported in posi- 125 130

tion in said compartment with its axis at an angle to the normal, a lamp projecting into said reflector, an opening at the rear of said partition for the passage of light into said 5 chamber, a rotary drum surrounding said reflector, and a stationary drum surrounding said rotary drum, substantially as described.

3. An illuminated apparatus for displaying an object comprising a stage-like chamber open at its front, a compartment in said 10 chamber hidden from external observation and separated from the rest of the chamber by a partition, a reflector supported in position in said compartment with its axis at an 15 angle to the normal, a lamp projecting into said reflector, an opening at the rear of said partition for the passage of light into said chamber, a rotary drum surrounding said reflector, and a supplementary reflector dis- 20 posed exterior to and at the rear of said rotary drum and adapted to receive rays of light from said reflector and to reflect them on to the object, substantially as described.

4. An illuminated apparatus for displaying an object comprising a stage-like chamber open at its front, a compartment in said 25 chamber hidden from external observation and separated from the rest of the chamber by a partition, a reflector supported in position in said compartment with its axis at an 30 angle to the normal, a lamp projecting into said reflector, an opening at the rear of said partition for the passage of light into said chamber, a rotary drum surrounding said 35 reflector, a stationary drum surrounding said rotary drum and a supplementary reflector

disposed exterior to and at the rear of said stationary drum, and adapted to receive rays of light from said reflector and reflect them on to the object, substantially as described. 40

5. An illuminated apparatus for displaying an object comprising a stage-like chamber open at its front, a compartment in said chamber hidden from external observation and separated from the rest of the chamber 45 by a partition, a reflector supported in position in said compartment with its axis at an angle to the normal, a lamp projecting into said reflector, an opening at the rear of said partition for the passage of light into said 50 chamber, a rotary drum surrounding said reflector, and supplementary reflectors at the rear of and at the sides of said rotary drum, substantially as described.

6. An illuminated apparatus for displaying an object comprising a stage-like chamber open at its front, a compartment in said chamber hidden from external observation and separated from the rest of the chamber 55 by a partition, a reflector supported in position in said compartment with its axis at an angle to the normal, a lamp projecting into said reflector, an opening at the rear of said partition for the passage of light into said chamber, a rotary drum surrounding said 60 reflector, a stationary drum surrounding said rotary drum, and supplementary reflectors at the rear of and at the sides of said stationary drum, substantially as described. 65

In testimony whereof, I affix my signature. 70

WEBSTER JOHN BEVILLE.
